UNITED STATES PATENT OFFICE

97,841

DESIGN FOR A BROILER GRILL

Joseph Cohen, Los Angeles, Calif.

Application August 7, 1935, Serial No. 57,992

Term of patent 3½ years

To all whom it may concern:

Be it known that I, Joseph Cohen, a citizen of the United States, residing at Los Angeles, in the county of Los Angeles and State of California, have invented a new, original, and ornamental Design for a Broiler Grill, of which the following is a specification, reference being had to the accompanying drawing, forming a part thereof.

Fig. 1 is a top plan view of my broiler grill, showing my new design.

Fig. 2 is an end elevational view thereof, and Fig. 3 is an enlarged sectional view taken on line 3—3 of Fig. 1.

I claim:

The ornamental design for a broiler grill, as shown.

JOSEPH COHEN.
